DOUBLE BELT CARRIER

James L. Baldwin, Oak Park, Ill.

Application April 12, 1935, Serial No. 16,009

7 Claims. (Cl. 198—165)

My invention relates to improvements in double belt carrier in which a single belt is employed and is placed to pass over suitable pulleys or idlers wherever necessary and doubled to carry papers or light parcels between the two strands of belt; and the objects of my improvement are, first, to make a simple, cheap and practical device; second, to carry papers safely, swiftly, and noiselessly from one place to another; be that up or down or horizontally; third, to provide a means for causing the double strands of the belt to tightly contact one another so that any paper placed therebetween will not fall therefrom by gravity; fourth, to provide adjustable pulley shaft brackets so the belt pulleys can be properly placed in position; and other objects to become apparent from the description to follow.

To describe my invention so that others versed in the art to which it pertains can make and use the same I have illustrated it on the two accompanying sheets of drawings forming a part of this specification and in which, Figure 1 is an elevation of a carrier built in accordance with my invention connecting the first, second and third floors of a building; Fig. 2 is an enlarged view of one of the pulley shaft adjustable brackets; Fig. 3 is a sectional view taken on line 3—3 of Fig. 2; Fig. 4 is a face view of one of the members shown in Fig. 3; Fig. 5 is an end view of another member seen in Fig. 3; Fig. 6 is an enlarged elevation of the station seen in Fig. 1, on the third floor; Fig. 7 is a side elevation of the station seen in Fig. 6, and Fig. 8 is a similar view to Fig. 6, with the floor of the receiving station dropped to automatically send all parcels received at the station to the next station in the system. Similar reference numerals refer to similar parts throughout the several views.

The three floors of a building are represented at 10, 11 and 12; a single belt 13 extends throughout the system and is double in its entire course except where it passes through a station.

The station on the lower floor 10 is provided with a belt tightener 14 arranged to slide vertically on the uprights 15 and automatically held in its uppermost position by a weight 16 secured to the end of a cable passing over suitable idlers 17, the other end of the cable being secured to the belt tightener 14 carrying the idler 18. A single strand of the belt 13 passes over the idler 18 thus tightening the belt 13 throughout its entire length.

The endless belt 13 is constantly driven by a suitable motor 19 preferably located at the lowest station on the first floor 10. The motor

19 is shown mounted on a platform 20 made adjustable vertically on the upright standards 15 so that the belt 21 can be tightened at will by lowering the platform 20. The belt 21 extends from around the motor pulley to around a large pulley 22 secured to the same shaft as the pulley 23. The belt 13 passes about the pulley 23 and is thus constantly driven. As stated above, the belt 13 is double throughout except where it passes through a station. Each station is provided with a receiving platform 24 and a sending platform 25 and the belt 13 extends about these two platforms at each station in single strands, as clearly seen in Figs. 6 and 8.

The belt 13 is constantly traveling in the direction indicated by the arrows in Figs. 1 and 6. As shown the station on the second floor 11 has its receiving platform 24 stationary so that all parcels carried to this station will be delivered on said platform 24, but the station on the third floor 12 has its receiving platform 24 hinged at 26 so that parcels carried to this station may be delivered here or may be automatically passed through this station by swinging the platform 24 down as seen in Fig. 8.

As shown in Fig. 6, the belt 13 is double as it passes up over the idler 27, leaving idler 27 passing downward one strand of the belt passes to the left under idler 28 and the other strand of the belt passes down around the left side of idler 29 thence down around the under side of idler 30, thence to the left around the left side of idler 31 thence to the right over idler 32 and thence downward. The other strand of the belt 13 after passing under the idler 28 passes to the left over idler 33 thence down under idler 31 on top of the other strand of the belt and from this point under idler 31, so that the two strands pass lying together to the next succeeding station. Thus it is seen that the two strands are lying together throughout their course except while passing through a station and it will be understood that it is while the double belt is traveling from one station to another that a paper or parcel is being carried between the two belts. To have the two strands of the belt hug close to each other to prevent such parcels or papers from falling away therefrom by gravity while being thusly carried the double belt is twisted as clearly shown in Fig. 1. From experience it is found that the double belt need be twisted only when there is considerable space between two idle pulleys over which the double belt passes.

Each receiving compartment is preferably pro-

vided with a short extending shelf 34 a short distance below the idler 29 for the purpose of aiding to have the papers brought into the station and deposited by gravity in a flat horizontal position upon the receiving platform 24. When the receiving platform is lowered as shown in Fig. 8, this extension or shelf 34 will also serve to have the papers slide down in proper position to have the advance edge enter between the two strands of the belt 13 passing about the idler 31, from whence it will be carried between the two strands of the belt to the next succeeding station. The one side of each station is preferably closed by a sheet of metal to prevent molestation of the papers by air currents or unscrupulous persons. Each station is provided with one rectangular piece of sheet metal 35 and one triangular piece of sheet metal 36, each of which are made removable so that they can be placed on the proper side of the station. Each removable sheet is provided with a forked lower edge 37 to straddle the upper edge of the stationary side 38 and its upper edge is forced into proper position under suitable springs 39 secured to the stationary side piece 38. Suitable springs 40 are secured to the stationary frame to hold the receiving bottom 24 in place when in its up position. The platform 24 is preferably provided with two vertical rods 41 connecting its free end with the free end of a hinged plate 42 arranged to swing about the hinge 43, so that the plate 42 will always move in unison with the platform or bottom 24.

Suitable brace rods or tubes 44 are connected between the uprights 15. The shafts 45 of all the idlers are preferably mounted in ball bearings and these are clamped tightly in brackets 46 which are secured adjustably to the uprights 15. As shown in Figs. 2 to 5 inclusive, the bracket 46 is adjustably secured to the pivot block 47 by set screw 48, the pivot block 47 is adjustably secured to the clamp 49 by the set screw 50 and the clamp 49 is adjustably secured to the upright 15 by the clamp screw 51. The clamp screws 48, 50 and 51 are made the same length and interchangeable so that a novice assembling the mechanism cannot misplace the clamp screws. A set-screw 52 is provided to hold the bracket 46 in proper adjusted position. To enable such adjustment the pivot block 47 is provided with a rectangular end 53 made to slide in the groove 54 provided in the one end of the elongated bracket 46. It will be noted that the pivot block 47 is made conical at 55 where it fits into a co-operating socket in the clamp 49. This construction makes a tight fit at this point and prevents any possible slipping.

It is seen from the above description that I have developed the belt drive to both accommodate the particular station arrangement and fit compactly in the stand or frame defining the station. The single belt sections are in the nature of a quadrilateral enclosure providing an upper entrance to the station at one side and a lower exit therefrom at the other, placing these units diagonally from each other in the frame. The transverse belt sections are thus above and below the platform groups, while the vertical ones travel between pairs of the frame uprights, leaving the space within the frame clear of moving parts. Nothing is therefore in the way of removing articles from the receiving platform or depositing articles on the sending platform. Further, the idlers 28 and 30, while carried by the frame, are entirely outside the zone of the

platforms, the idler 30 being nested in the triangular space below the platform 25, so that all running and adjusting elements are outside the field of approach, making access to the station and its contents safe at all times.

Having thus fully described my invention what I claim as new and desire to secure by Letters Patent of the United States is:—

1. In a device of the class described, a parcel receiving and sending station provided with an upright frame, a plurality of belt wheels, a receiving platform in the upper part of the station, a sending platform in the lower part of the station, a plurality of belts passing over said belt wheels, means for driving the belts and means whereby the one end of the receiving platform can be lowered to deposit all received parcels on the sending platform to deliver the same between the departing belts.

2. In a device of the class described, as specified in claim 1 and means for retaining the one end of the receiving platform in either a raised or lowered position.

3. In a device of the class described, as specified in claim 1 and means movable in unison with the receiving platform for directing the incoming parcels downward toward the departing belts.

4. A belt conveyor comprising an upright frame, article receiving and sending platforms in the upper and lower parts thereof respectively, an article-depositing belt drive leading to the receiving platform, an article dispatching belt drive leading from the sending platform, and means to lower the receiving platform to direct received articles upon the sending platform for transfer to the dispatching belt drive.

5. A belt conveyor comprising an upright frame, a double belt drive entering the same at one side from above and separating, a pulley at the opposite side of the frame and receiving one belt section directed laterally from said drive and training the same downwardly along said opposite side, a second pulley below said drive receiving the other and downwardly directed belt section therefrom and training the same laterally toward the lower portion of said first belt section, a third pulley receiving said belt sections to combine them as a departing double belt drive, article receiving and sending means arranged in the quadrilateral enclosure formed by the said belt sections and cooperating respectively with the entering and departing double belt drives, the frame having laterally spaced pairs of corner posts at both sides, and said downwardly directed belt sections extending between correspondingly-located pairs of corner posts.

6. A belt conveyor comprising an upright frame, a double belt drive entering the same at one side from above and separating, a pulley at the opposite side of the frame and receiving one belt section directed laterally from said drive and training the same downwardly along said opposite side, a second pulley below said drive receiving the other and downwardly directed belt section therefrom and training the same laterally toward the lower portion of said first belt section, a third pulley receiving said belt sections to combine them as a departing double belt drive, article receiving and sending means arranged in the quadrilateral enclosure formed by the said belt sections and cooperating respectively with the entering and departing double belt drives, idlers carried by the first-mentioned side of the frame and receiving the laterally-directed belt sections underneath, and means to adjust the idlers down-

wardly to take up slack in such belt sections and maintain tension between said drives.

7. A belt conveyor comprising an upright frame, a double belt drive entering the same at one side from above and separating, a pulley at the opposite side of the frame and receiving one belt section directed laterally from said drive and training the same downwardly along said opposite side, a second pulley below said drive receiving the other and downwardly directed belt section therefrom and training the same laterally toward the lower portion of said first belt section, a third pulley receiving said belt sections to com-

bine them as a departing double belt drive, article receiving and sending means arranged in the quadrilateral enclosure formed by the said belt sections and cooperating respectively with the entering and departing double belt drives, said receiving means being a horizontal platform, said sending means being a platform inclined toward the departing double belt drive, and said second pulley being disposed in the space between the under side of the inclined platform and the first- 10 mentioned side of the frame. 5
